UNITED STATES PATENT OFFICE.

CHARLES N. MORRIS, OF CINCINNATI, OHIO.

DEVICE FOR GRAINING ZINCOGRAPHIC AND LIKE PLATES.

SPECIFICATION forming part of Letters Patent No. 236,824, dated January 18, 1881.

Application filed September 17, 1880. (No model.)

To all whom it may concern:

Be it known that I, CHARLES N. MORRIS, of Cincinnati, in the county of Hamilton and State of Ohio, have invented a new and useful 5 Device for Graining Zincographic and like Plates, of which the following is a specification.

My invention relates to mechanism for producing the proper grain or plain granular surface upon a zinc or other plate or slab to adapt 10 it to receive a crayon or pen drawing for printing purposes, by the action, in conjunction with any suitable abradant, of rollers automatically rotated.

15 The device employed by me for the purpose consists of two or more rollers, preferably of conical shape, and of some heavy and moderately-hard material, and so journaled upon a horizontally-whirling axle as for their peripheries to rest tangentially upon the surface to be operated upon. The said axle has a vertical shank so confined in the lower end of a 20 vertically-slotted driver as, while being revolved thereby in a plane parallel to the face 25 of the work, to be at liberty to rise and fall freely, so as to secure uniform action on all portions of the plate or slab undergoing operation.

In order that my invention may be fully understood, I will proceed to describe it with 30 reference to the accompanying drawings, in which—

Figure 1 is a perspective view of a graining-machine embodying my invention. Fig. 2 35 represents a pair of my conical graining-rollers, half in axial section and half in elevation. Fig. 3 shows my driver in side elevation. Figs. 4 and 5 represent modifications of my invention, in which the graining-rollers are of 40 cylindrical form and are journaled upon a straight axle.

A represents the frame of a machine whose construction (with the exception of the driver and the graining-rollers) may be substantially 45 that of an ordinary engraver's routing or sand-papering-machine, B being the usual vertically-adjustable table of such a machine; C, the standard, supporting the customary folding crane D, having the usual vertical mandrel F, driven by steam or other power, and the represented unusually long guiding-handle

E, having about twice the radial sweep of the mandrel-frame.

Firmly attached to the lower extremity of mandrel F, by a screw, g, or other means, is 55 my driver G, whose lower end has a vertical notch or slot, g', to receive a shank or stem, H, that extends upward from a bent axle or stud-shaft, I. Both slot g' and stem H are bounded by flat and vertically-parallel walls, so as to 60 compel corotation of driver and stem, and thus produce the desired horizontal swing or whirl of the rollers, while permitting said rollers to follow to any desired extent the inequalities or lack of horizontality of plate-surface. The 65 upper extremity, g'', of the driver has the represented cup form, to retain any grease that may reach that part.

Collars i hold the axle to its proper longitudinal position in the driver, and other collars, i', coact with nuts L upon the screw-threaded extremities i'' of the axle, so as to hold the rollers in place upon the axle, while permitting their free rotation thereupon. The rollers proper, K, are preferably of zinc, and are cast 75 solidly upon cast-iron or brass hubs M. Washers N, of any suitable material, are interposed between the hub ends and the said nuts and collars. The hubs M are chambered out, as at m, with the double object of diminishing 80 friction and of serving as retaining-chambers or reservoirs for any lubricant without danger of its spillage upon the work, or for reception of a greased sleeve or packing.

The pitch of the screws i'' at the extremities 85 of the bent axle is necessarily in opposite direction to that of the screw g by which the driver is attached to the mandrel, in order that the operation of the machine shall tend rather to tighten than to loosen the said screws. In 90 the present illustration the screw-threads are arranged for a left-hand revolution of the rollers, the pitch of the driver-coupling being with this intent left-handed, while the axle-threads are right-handed.

In operation the plate Z to be surfaced is secured upon the table B, and, a suitable abradant—such as fine sand, emery-flour, or other hard angular and gritty powder—being scattered upon the plate, the rollers are secured in 100 the driver, and the table is adjusted to proper height. The operator then grasps the handle

E and starts the machine in motion, guiding the rollers above the work by means of the handle, so as to cause a cyclonic action thereof.

The above-described preferred form of my invention may be varied in non-essential particulars. For example, each roller may be composed of a gang of independently-revolving cylinders upon a straight axle, as represented in Fig. 4, and these component cylinders may increase in longitudinal dimensions toward the outer extremities of the axle, as in Fig. 5.

In place of or in conjunction with the use of an abradant upon the plate, the operating-faces of the rollers may be composed of an abrading material.

Instead of zinc I may employ glass, stone, or other suitable material for the rollers.

The rollers proper, especially when of so different a material to that of the axle as glass, may journal solidly upon the axle-arms, as shown in Fig. 4, and a dry lubricant, such as plumbago, be employed, or lubricants be dispensed with.

The pressure of the graining-rollers may, if desired, be increased or regulated by weights or a spring bearing upon the top of the axle-stem.

While preferring two rollers, as here illustrated, a greater number may be employed. For example, three or four radial arms for an equal number of rollers may be employed, and the alternate rollers may be of diverse diameters and radial sweep, and with independent play or self-adjustment upon the plate.

I have used and prefer for the material of the washers bacon-rind cut into suitable annular disks; but said washers may be composed of metal or other suitable material.

An obvious modification consists in forming the driver with a square or flat tenon, which occupies, with sufficient play in the plane of self-adjustment, a corresponding mortise or socket in the axle, or each axle-arm may be independently hinged to the driver.

The rollers may be cast solidly upon their shafts, said shafts being journaled in the swinging bar.

The mandrel-frame may be a stationary one, and the lateral shift or travel be secured by moving the table.

I am aware that rollers, both conical and otherwise, have been journaled in swinging frames for various uses in the arts, and that folding cranes or mandrel-frames have been employed for journal-bearings of routing-bits, &c. I therefore disclaim novelty in such rollers and bearing-frames, separately considered.

Having thus described my invention, the following is what I claim as new and desire to secure by Letters Patent:

The zincographic graining apparatus, consisting of balanced rollers K upon a swinging shaft, I, whose stem H occupies vertical slot g' in the driver or mandrel G, so as, while compelling corotation, to permit vertical play of the rollers, in the described combination with folding crane-bearing D of said mandrel, provided with guiding-handle E under control of the operator, as set forth.

In testimony of which invention I hereunto set my hand.

CHAS. N. MORRIS.
